UNITED STATES PATENT OFFICE.

ARTHUR JAMES POSTANS, OF LONDON, ENGLAND, ASSIGNOR TO THE ADDER CASH REGISTER SYNDICATE LIMITED, OF LONDON, ENGLAND.

PRINTING MECHANISM FOR CASH-REGISTERS OR LIKE MACHINES.

No. 894,982.

Specification of Letters Patent.

Patented Aug. 4, 1908.

Application filed August 27, 1907. Serial No. 390,335.

To all whom it may concern:

Be it known that I, ARTHUR JAMES POSTANS, a subject of the King of England, and residing at London, England, have invented certain new and useful Improvements in Printing Mechanism for Cash-Registers or Like Machines, of which the following is a specification.

This invention is for improvements in or relating to printing mechanism for cash registers or like machines.

Cash registers and like machines wherein the amounts recorded are printed on to a record strip are well known. The printing is usually effected by rotatable printing drums and the present invention has for one of its objects to provide a simple form of mechanism comprising an operating handle or key so connected with the printing drums, and with a coöperating platen that when the key is moved in one direction it first effects relative movement of the drums and platen for the purpose of printing and then by its continued movement zeroizes the drums.

Any suitable form of zeroizing mechanism may be employed for the drums, but if it is desired to coöperate with the platen as stated above, such mechanism preferably comprises a cam-shaft that coöperates with a series of zeroizing fingers. These latter move outwardly prior to or during the operation of printing and then carry the drums round to the zero position after printing has taken place. The mechanism which operates the cam-shaft for zeroizing in this case, is operatively connected with mechanism whereby the platen is advanced for the purpose of printing and the same mechanism may return it to its normal position ready for the next series of operations. If desired, however, separately operated zeroizing mechanism may be employed, but this is not so convenient as it is desirable to perform the whole operation by the movement of one key.

The platen according to this invention is preferably loaded, for instance by a spring, and is normally retained by a movable stop in such position that it is held away from the printing drums although its spring constantly tends to move it against the same. The platen is conveniently mounted in a pivoted frame to which the spring is attached and an arm connected with the frame rests upon the movable stop whereby the advance of the platen is prevented. A key is operatively

connected with the stop and at the first movement of the key, the stop is carried out from engagement with the platen carriage, so that the latter advances under the action of the spring, and the platen carrying the recording strip, strikes the printing drums so that the amount recorded thereon is printed. Further movement of the key then zeroizes the drums as hereinafter described and returns the platen to its normal position by means of a cam. The cam at the same time advances an auxiliary stop whereby the platen carriage is held in position until the key is freed and allowed to return to its normal position; during this return the main stop is brought into position to engage the platen carriage and the auxiliary stop is displaced.

The particular form of zeroizing mechanism preferred is described in my specification Ser. No. 390,334 of even date as it is applicable to mechanisms other than printing devices but it is also described in the present specification so that all the coöperating parts of the printing mechanism may be included in the one specification.

In the accompanying drawings which illustrate one method of carrying out this invention, Figure 1 is a side elevation of the printing mechanism with the platen in the normal position, Figs. 2, 3 and 4 are similar views showing the parts of the mechanism in different positions, Fig. 5 is a plan of Fig. 1 with the platen swung back beyond its normal position and the printing drums removed, Fig. 6 shows on a larger scale the drums with their zeroizing mechanism viewed from the right of Fig. 1, Fig. 7 is a section on the line 7—7 of Fig. 6, Fig. 8 is an end elevation of the mechanism shown in Fig. 6 viewed from the right and Fig. 9 is a section on the line 9—9 of Fig. 6.

Like letters indicate like parts throughout the drawings.

A key H is pivoted at H¹ to a suitable part of the frame of the machine, the key being of course accessible from outside the casing, while the parts connected therewith lie mainly within the casing. The lever H has a rear extension H² which is slotted at H³ to receive a pin J¹ on an arm J. The arm J is carried by a shaft C¹ free to rock in bearings formed on a frame K. The shaft has fast upon it a toothed quadrant C² that gears with a toothed wheel C³. This wheel is fast

on a cam-shaft C forming part of the zeroizing mechanism which is more particularly described with reference to Figs. 6 to 9, and concentrically mounted with the shaft are 5 the printing drums A also described in detail in connection with the same figures. The shaft C⁴ is controlled by a spring C¹¹ secured at one end to the quadrant C³ and at the other end to part of the frame of the machine, as 10 for instance to the pin H¹ whereon the lever H is pivoted. The spring C¹¹ thus always tends to turn the shaft in the direction of the arrow (Fig. 1) and thereby retains the rack C³ in its normal position and also the key H 15 in the raised position against a stop H^{2*}.

The platen L is rotatably carried on pivots L¹ fast on a frame or carriage L². This frame comprises two side plates connected together by a rear wall L⁶ and by transverse rods L³ L⁴ (Fig. 5). The lower ends of the plates are pivoted on a transverse spindle L⁵. Free on the spindle L⁵ is a sleeve M carrying an arm M¹ and at the end of this arm is a roller M². The sleeve also carries two 25 short arms M³ whose ends bear against the rear wall L⁶ of the platen frame. The frame is free to move relatively to the arms M³ but is normally maintained against the latter by springs L⁷ which are connected to the trans- 30 verse rod L³ at one end and to a fixed frame member K¹ at the other end. The tension of the springs is such that if the frame L² were unchecked they would swing the same about the spindle L⁵ and bring the platen L 35 against the recording drums A. Normally, however, the platen is maintained free of the drums in the position shown in Fig. 1. This is effected by a movable stop N which is shaped at its end to receive the roller M² of 40 the arm M¹. The stop N is carried fast on the rocking shaft C⁴ and in advance of it and situated in the same plane as the stop and also fast upon this shaft is a cam or cam-faced arm N¹. The arm N has a pin N² which projects 45 in a direction away from the observer (Figs. 1 and 5) and the arm N¹ carries a similar pin N³. Between these two pins and loose upon the shaft C⁴ is an auxiliary stop O whose end O¹ is shaped to receive the roller M² of the 50 arm M¹. It will be seen that the platen L is thus loaded or spring-controlled, so that immediately the arm M¹ is released it is drawn forward by the springs L⁷ until it is arrested by the drums A.

55 The drums have cut on their faces a series of figures as indicated by the ciphers (Fig. 6) and the operating mechanism of the drums is connected with the keys of the cash register in such manner that after any item has 50 been recorded on the machine by depressing the proper keys the drums will be turned into such positions as to bring the numbers corresponding to such item into printing position. After the operator has thus recorded 65 the item on the machine, he depresses

the key H and in doing so rocks the shaft C⁴ in clockwise direction. The first movement of the key thus carries the movable stop N from under the roller M² whereby the frame or carriage L² is released so that 70 the springs L⁷ cause the platen L to strike against the drums A. The platen carries a paper strip indicated at X (Fig. 1) which is fed around the same between suitable guides and a ribbon is interposed between the 75 platen and drums A so that an ink impression is made upon the paper strip. As such ribbon mechanism and paper guides form no part of the present invention, there is no need to describe these in detail and the ribbon with this mechanism is omitted for the 80 sake of clearness, from the drawings.

In part of the frame K² of the machine is a resilient stop or buffer P (Figs. 1 and 5). This stop comprises a plunger controlled by 85 a spring P¹ and the spring is sufficiently strong to force the platen carriage back against the action of the springs L⁷ immediately after the platen has been arrested by the type drums. This plunger is alined to 90 bear against the transverse rod L³ of the platen carriage.

In Fig. 2 the platen is shown in the printing position, its momentum having caused it to force the plunger P back against its 95 spring but directly the platen and its carriage are arrested by the type drums they resume the position indicated by the chain line circle L⁸ shown in that figure. The roller M² now lies in the recess between the 100 stop N and the cam N¹ so that further downward movement of the key H forces the cam against the roller and thus lifts the arm M¹ into the position shown in Fig. 3. As the arms M³ are carried on the same sleeve 105 as the arm M¹ and bear against the rear wall L⁶ of the platen carriage L², this movement causes the carriage also to be swung back against the action of the springs L⁷. In Fig. 3 the roller is shown nearly at the top of 110 the cam N¹ and the pin N³ carried by the cam has come into contact with the auxiliary stop O so that this has been moved rearwardly. The engaging end O¹ of the stop is shaped so that its rearward end lies slightly 115 above the cam as shown at O² while the engaging portion O¹ already referred to lies flush with or below the cam. It thus follows that a still further downward movement of the key H causes the part O² of the auxiliary 120 stop to be forced under the roller M² of the arm M¹ so that the roller enters the recess O¹ as shown in Fig. 4. The key H has now been carried to the limit of its downward movement, so that it bears against a stop H⁴ 125 conveniently carried by the casing of the machine, part of which is shown at H⁵, and it is next released for the purpose of permitting it to return to its normal position under the action of the spring C¹¹. During the re- 130

turn movement of the key the shaft C⁴ is rotated in a counter-clockwise direction so that the cam N¹ is carried away from the roller M² which latter continues to be supported by the auxiliary stop O. Before, however the key H arrives at its normal position the pin N² on the movable stop N comes into contact with the auxiliary stop O and pushes the same in the direction of the arrow (Fig. 4) from beneath the roller. As however the auxiliary stop is removed from under the roller the main stop N comes beneath the same when all the parts resume the position shown in Fig. 1.

It should be noted that the projection O² on the auxiliary stop O is rounded so that when the stop N is carried from beneath the roller M² it shall not be detained by the auxiliary stop O. This latter stop being free may come into contact with the roller as it is released from the stop N but by rounding the projection O² as described it will be forced back by the roller as the latter descends so as not to interfere with the release of the platen.

The downward movement of the key H in addition to first releasing the spring-controlled platen L and then returning it to its normal position, also zeroizes the printing drums A. This is effected by the rack C³ which meshes with the pinion C² of the zeroizing mechanism which latter is herein-after fully described with reference to Figs. 6 to 9, but it should be noted that the key at the beginning of its movement effects the printing while its continued movement in the same direction zeroizes the drums; moreover the movement of the one key prints, zeroizes the drums and returns the platen mechanism to the normal position.

Pivoted at Q to one of the side plates of the platen carriage L² is an arm Q¹. This arm has pivoted to it at one end a pawl Q² (Fig. 1) which engages a ratchet wheel Q³ fast on the platen L. That end of the arm or lever Q¹ remote from the pawl Q² has a cam-face Q⁴ adapted to coöperate with a stop Q⁵ fast on the frame of the machine. The lever Q¹ is maintained in contact with the stop by a spring Q⁶.

The operation of this mechanism is as follows:—When the platen carriage is released so that it advances to the printing position the lever Q¹ is rocked by its spring, about its pivot Q so that the end which coöperates with the stop Q⁵ rises as shown in Fig. 2 and the pawl Q² is thereby drawn back one tooth over the ratchet Q³. It follows therefore that as the platen-carriage is returned to the normal position the cam-faced end of the lever will be depressed, as the part Q⁴ passes under the stop Q⁵, and thus the pawl Q² will now be advanced and carry the ratchet wheel Q³ forward one tooth. By this means the platen is rotated one step at

each movement away from the printing position.

It will be seen that when the platen is in the normal position the stop Q⁵ engages the extreme end of the cam-face Q⁴ and the lever Q¹ has an extension Q⁷ whose outer face is concentric with the center L⁵ about which the platen carriage turns when the lever is in the position shown in Fig. 1. The object of this arrangement is to permit the platen carriage to be swung back against the action of its springs L⁷ into the position indicated in chain line in Fig. 1 so that the item last recorded can be read. The platen carriage preferably lies entirely outside the casing of the machine, but the recorded amount cannot be conveniently read without thus swinging it back. This backward movement however does not effect rotation of the platen as the extension Q⁷ is then in engagement with the stop Q⁵ so that the lever Q¹ does not move relatively to the platen carriage. The arms M³ do not interfere with this backward movement of the carriage as they have no connection with the carriage but only serve as stops against which the rear wall L⁶ of the carriage is made to bear, as already described, by the action of the springs L⁷.

The zeroizing mechanism is constructed as follows:—The drums A are mounted free on a rotatable sleeve B carried in brackets B*. The normal driving mechanism for the drums is of known construction and comprises a toothed quadrant A¹ which engages a pinion A² also mounted free upon the sleeve B. The pinion carries a disk A³ whereon is pivoted at A⁴ a spring-controlled pawl A⁵. Each drum has secured to it either directly or through the medium of a sleeve A⁶ a disk A⁷ having a series of pins A⁸ which serve as teeth where-with the pawl A⁵ coöperates. The quadrants A¹ are actuated by the keys of the machine and move a greater or less distance according to the value of the key that is operated. Any mechanism may be used for this purpose such for example as that described in my earlier patent No. 786,839 and it may be assumed that the mechanism is arranged in such manner that when the key is depressed the quadrant is moved in the direction of the arrow, Fig. 9 and draws the pawl A⁵ back over the pins A⁸. The mechanism is spring controlled whereby on releasing the key the quadrant is returned and the pawl now engaging with the last pin over which it was withdrawn carries the drum A round with it until it again arrives at the position of rest. It will thus be seen that each of the drums is brought round to varying positions according to the number and the value of the keys operated whereby numbers of different values on the drums A are brought into the printing position. As however, it is desired to print each item recorded upon the

machine, these drums must be set back to the zero position after each printed record has been made.

To effect the zeroizing a series of collars or casings B^1 is secured on the hollow shaft or sleeve B , one collar being allotted to each drum A . The collar has a radial lug B^2 and mounted in this portion is a setting finger or pin B^3 . The pin B^3 has an enlarged head B^4 and is surrounded by a spring B^5 which bears at one end against the head B^4 and at the other end against the interior of the lug so that it always tends to advance the pin towards the center of the sleeve B and the sleeve is perforated to allow the passage of the head therethrough. Within the sleeve B is the cam shaft C already referred to. This shaft is recessed as at C^1 opposite each pin B^3 , and when the cam shaft is in its normal position relatively to the sleeve the recesses C^1 lie directly beneath the pins so that the latter are advanced into them; the outer end of each pin then lies within the lug B^2 of its casing B^1 .

At one end the cam shaft C carries the pinion C^2 which has already been described as meshing with the toothed quadrant C^3 and at the other end the shaft carries a radial pin C^4 (Fig. 8) which is situated adjacent to a disk B^6 carried fast on the sleeve B . On the disk are two pins B^7 B^8 which lie in the path of the pin C^4 so that while the shaft C is allowed a certain amount of free movement relatively to the sleeve B it finally engages the sleeve B by means of its pin C^4 and one of the pins of the disk B^6 . The object of permitting this free movement is to enable the shaft C to be turned so that the recesses C^1 therein may be carried away from the pins B^3 as shown in Fig. 7 before the sleeve B commences to rotate and in order that the sleeve may be held stationary while this operation is effected the disk B^6 has in it a notch B^9 and coöperating therewith is a spring-controlled 45 detent D . This disk B^6 thus serves as a cam and the detent or follower D drops into the notch B^9 when this is brought into such position that it registers therewith, but the engaging portion of the detent is so shaped that 50 when the disk is forcibly turned the detent will be made to rise out of the notch against the action of its spring.

With the mechanism arranged as shown in the drawings zeroizing is effected by turning the drums A in a direction opposite to that of their normal travel and as the pawls A^5 prevent movement in this direction it is necessary to disengage them before zeroizing can be effected. Obviously the mechanism might be arranged to zeroize by movement in the same direction as that in which they normally travel, but as it is always necessary in these machines to provide some locking device whereby over-running may be prevented, there would still be

some pawl or equivalent device to release before zeroizing could be effected. To release any such locking mechanism (in this case the pawls A^5) the movement of the retarding detent D is taken advantage of. For this purpose it is connected by a link D^1 to an arm E^1 fast on a rocking shaft E carried in brackets E^2 . On the rocking shaft is a series of arms E^3 , one of which is allotted to each pawl A^5 . When the parts are at rest, that is when the keys of the machine are all released so that they assume their normal positions, the pawls A^5 are all brought round by means of the quadrants A^1 and pinions A^2 to the position shown in Fig. 9 and each pawl carries a pin A^9 . The arms E^3 on the rocking shaft E are so aligned relatively to these pins that when the shaft is in its inoperative position, that is when the detent D lies in the notch B^9 of the disk B^6 the arms lie clear of the pawls A^5 as shown in Fig. 8, but when the detent is forced out of the notch the shaft E is rocked so that the arms advance and engage the pins A^9 on the pawls whereby the latter are pushed back out of engagement with the pin teeth A^8 of the drums.

The operation of this mechanism is as follows:—The quadrant C^3 is advanced in a clockwise direction as already stated by the depression of the key H and consequently the shaft C will be rotated in the direction indicated by the arrow in Fig. 8. When the shaft C is in its normal position the pin C^4 lies against the pin B^8 and consequently during the first quarter of a revolution the shaft advances without imparting movement to the sleeve B , this being held as already described by the detent D . After the first quarter of a revolution the pin C^4 is brought against the pin B^7 on the disk B^6 , but before it reaches the same the recesses C^1 on the shaft have been carried away from the pins B^3 , see Fig. 7, so that these have been moved outwardly against the action of their springs B^5 . Further movement of the shaft C now causes the sleeve B to rotate by means of the engagement of the pins C^4 B^7 and the pins B^3 are carried round with the sleeve. Each drum A has on it a pin A^{10} which is in such position that it clears the lugs B^2 of the collar B^1 allotted to that drum, but lies in the path of the pin B^3 when this is in the advanced position. The quadrant C^3 is moved a sufficient distance to rotate the sleeve B through a complete revolution so that whatever position each drum is in the pin B^3 allotted thereto will strike the pin A^{10} on the drum and carry it round until movement of the shaft is arrested. To insure that the drums shall be properly brought to zero a spring-controlled pawl is allotted to each drum and coöperates with the pin A^{10} . This pawl allows the pin to pass freely beneath it when the drum is moving in the normal di-

rection, see the arrow Fig. 7, but when the drum is moved in the reverse direction as for zeroizing it engages the pin A¹⁰ when the drum has been brought round to the zero position. In Fig. 7 the parts are shown in the position they occupy when the shaft C has just completed its movement and it will be seen that the pin A¹⁰ is locked between the pin B³ and the detent F, the drum A being in the zero position.

When the key H has been released the quadrant C³ and also the shaft C⁴ automatically return to their normal position and in so doing the quadrant by means of the pinion C² returns the shaft C to its normal position. During the first quarter of a revolution in the return movement of the shaft C the sleeve B may or may not move with it, that is to say if the friction between the sleeve and shaft is greater than that between the sleeve and its bearings B⁸ the sleeve will follow the shaft, but if the reverse is the case the sleeve will be held by the bearing until the pin C⁴ comes into contact with the pin B⁸, when the sleeve will be carried round until the shaft comes to rest at its normal position. When the shaft has come to rest the sleeve B will have been returned to the position shown in Fig. 8 so that the detent D once again engages the notch B⁹ of the disk B⁶. It will be seen that if the sleeve is not held by the bearing the sleeve B will travel round with the shaft until the detent D enters the notch B⁹ when the sleeve will be arrested and the shaft C will continue its movement independently until the pin C⁴ once again lies against the pin B⁸. As the detent D drops into the notch B⁹ it rocks the shaft E back to its release position so that the pawls A⁵ of the drums are again operative.

What I claim as my invention and desire to secure by Letters Patent is:—

1. In printing mechanism for a recording machine the combination of, a rotatable recording unit, a platen opposed to the unit and movable to and from the same, a spring that always tends to move the platen towards the recording unit, a movable stop that normally retains the platen away from the unit, a cam movable with this stop, a controlling member operatively connected with the cam and stop in such manner that displacement of the stop releases the platen for printing and continued movement of the controlling member brings the cam into operation to return the platen, an auxiliary stop, operative connection between the auxiliary stop and the controlling member whereby the stop is brought into position to temporarily hold the platen in its inoperative position when the cam has returned it and operative connection between the controlling member and the auxiliary stop whereby the latter is displaced on the return movement of the member as the main stop is again re-

turned to position by the return movement controlling member, substantially as set forth.

2. In printing mechanism for a recording machine the combination of, a rotatable recording unit, means for operating this unit, a platen opposed to the unit and movable to and from the same, a spring that always tends to move the platen towards the recording unit, a movable stop that normally retains the platen away from the unit, an auxiliary stop for retaining the platen in its normal position away from the recording unit, a movable controlling member, means operatively connecting the movable stop with the controlling member so that movement of the latter in one direction displaces the stop and permits the advance of the platen for printing, means operatively connecting the controlling member with the platen so that continued movement of the member returns the platen to its normal position, means operatively connecting the auxiliary stop with the controlling member so that this is brought by the latter into position to retain the platen in its withdrawn position, and means operatively connecting the movable stop with the auxiliary stop in such manner that the completed movement of the controlling member causes the movable stop to displace the auxiliary stop and engage the platen without releasing the platen, substantially as set forth.

3. In printing mechanism for a recording machine the combination of, a rotatable recording unit, means for operating this unit, a platen opposed to the unit and movable to and from the same, a spring that always tends to move the platen towards the recording unit, a rock-shaft, a controlling member for operating the rock-shaft, a stop carried by the rock-shaft and so disposed that when the rock-shaft is in its normal position the stop retains the platen away from the recording unit, a cam carried by the rock-shaft but disposed thereon in a different angular position from that occupied by the stop and arranged to engage and return the platen after the rock-shaft has been moved to release the platen by advancing the stop, an auxiliary stop having limited free movement relatively to the rock-shaft, means for operatively connecting the rock-shaft with this stop in such manner that when the shaft is turned to advance the cam against the platen the auxiliary stop is brought into the path of the platen and locks the same in its withdrawn position during the return movement of the rock-shaft and means for displacing the auxiliary stop when the movable stop is returned by the rock-shaft without releasing the platen, substantially as set forth.

4. In printing mechanism for a recording machine, the combination of, a rotatable recording unit, means for operating this unit, a

pivoted frame, a platen carried thereby and opposed to the unit, a spring that always tends to move the platen frame towards the recording unit, a movable stop to retain the 5 platen frame normally away from the unit and that permits the same to be moved beyond such normal position in a direction away from the unit, and a controlling member having operative connection with the 10 stop in such manner that it displaces the stop when the member is moved to effect printing, substantially as set forth.

5. In printing mechanism for a recording machine the combination of, a rotatable recording unit, means for operating this unit, a pivoted frame, a platen rotatably carried thereby and opposed to the unit, a spring that always tends to move the platen frame towards the recording unit, a movable stop 15 to retain the platen frame normally away from the unit and that permits the same to be moved beyond such normal position in a direction away from the unit, a spring-controlled arm pivoted to the platen frame and 20 having engagement with a stationary stop in such manner that the normal movement of the frame causes the arm to rock by reason of its engagement with the stationary stop, an extension to the arm so disposed that when 25 the frame is swung back beyond the normal position it retains its engagement with the 30

stationary stop but is not moved about its pivot, a pawl on the arm, and a coöperating ratchet on the platen the displacement of the arm caused by the movement of the platen 35 frame being sufficient to advance the ratchet step by step, substantially as set forth.

6. In printing mechanism for a recording machine the combination of, a rotatable recording unit, means for operating this unit, a platen opposed to the unit and movable to and from the same, a spring that always tends to move the platen towards the recording unit, a movable stop that normally retains the platen away from the unit, a controlling member having operative connection with the stop in such manner that it displaces the stop when the member is moved to effect printing and a yielding stop to check the advance of the platen under the action of 40 its spring the stop being so adjusted that when the platen is arrested thereby it first yields and allows the platen to strike the recording unit and then returns the platen 45 clear of the unit, substantially as set forth. 50

In testimony whereof I have signed my name to this specification in the presence of two subscribing witnesses.
